(57) **CLAIM**

The ornamental design for a container for acoustical drop ceiling grid members, as shown and described.

DESCRIPTION

FIG. 1 is front perspective view of a container for acoustical drop ceiling grid members according the first embodiment;

FIG. 2 is a rear perspective view of the container for acoustical drop ceiling grid members as shown in FIG. 1; FIG. 3 is a front view of the container for acoustical drop ceiling grid members as shown in FIG. 1; FIG. 4 is a rear view of the container for acoustical drop ceiling grid members as shown in FIG. 1; FIG. 5 is a first side view of the container for acoustical drop ceiling grid members as shown in FIG. 1; FIG. 6 is a second, opposite side view of the container for acoustical drop ceiling grid members as shown in FIG. 1; FIG. 7 is a top plan view of the container for acoustical drop ceiling grid members as shown in FIG. 1; FIG. 8 is a bottom view of the container for acoustical drop ceiling grid members as shown in FIG. 1; FIG. 9 is front perspective view of a second container for acoustical drop ceiling grid members according to the present invention; FIG. 10 is a rear perspective view of the container for acoustical drop ceiling grid members as shown in FIG. 9; FIG. 11 is a front view of the container for acoustical drop ceiling grid members as shown in FIG. 9; FIG. 12 is a rear view of the container for acoustical drop ceiling grid members as shown in FIG. 9; FIG. 13 is a first side view of the container for acoustical drop ceiling grid members as shown in FIG. 9; FIG. 14 is a second, opposite side view of the container for acoustical drop ceiling grid members as shown in FIG. 9; FIG. 15 is a top plan view of the container for acoustical drop ceiling grid members as shown in FIG. 9; FIG. 16 is a bottom view of the container for acoustical drop ceiling grid members as shown in FIGS. 9; and, FIG. 17 is a perspective view showing a user on a scaffolding, using the container for acoustical drop ceiling grid members as shown in FIG. 1 to hold grid members for an acoustical drop ceiling. Any broken lines shown are directed to environmental structure only. Such broken lines form no part of the claimed design.
